[57] CLAIM

The ornamental design for a check writing device, as shown and described.

DESCRIPTION

FIG. 1 is a left, front perspective view of a check writing device showing my new design, with the top open;

FIG. 2 is a top plan view thereof;

FIG. 3 is a front elevational view thereof;

FIG. 4 is a left side elevational view thereof, the right side elevational view being a mirror image thereof;

FIG. 5 is a rear elevational view thereof;

FIG. 6 is a bottom plan view thereof;

FIG. 7 is a left, front perspective view thereof, with the top closed.

*Fig. 3**Fig. 4**Fig. 5**Fig. 6**Fig. 7*
